BURGLAR ALARM SYSTEM

August Krueger, Chicago, Ill.

Application September 21, 1946, Serial No. 698,499

2 Claims. (Cl. 177—314)

1

The present invention relates to improvements in burglar alarm systems for doors.

One of the objects of the invention is to provide a burglar alarm system which is associated with a conventional door lock, and which will emit an alarm signal if the door knob or handle is tampered with when the door is locked.

A further object is to provide a burglar alarm system comprising a simple and inexpensive control switch unit which is adapted to be operatively associated with the keeper plate of the door lock, and which includes a series of switches operable respectively by the spring latch and sliding bolt of the lock to control the alarm signal.

Another and more specific object is to provide a burglar alarm system of the foregoing character having two switches connected in series in an electric alarm circuit, with one switch normally closed and adapted to be opened by the spring latch when extended, and with the other switch normally open and adapted to be closed by the sliding bolt when extended, whereby when the door is locked, retraction of the latch will close the alarm circuit.

Further objects and advantages will become apparent as the description proceeds.

In the accompanying drawings:

Fig. 1 is a fragmentary perspective view of a burglar alarm with a schematic representation of the alarm circuit, embodying the features of the present invention;

Fig. 2 is a fragmentary vertical sectional view through the control switch unit of the burglar alarm system;

Fig. 3 is a view similar to Fig. 2, but illustrating a modified form of the invention adapted particularly for automobile doors;

Fig. 4 is a transverse vertical sectional view taken along line 4—4 of Fig. 3;

Fig. 5 is a diagrammatic illustration of an electric alarm and ignition circuit, including the switch unit illustrated in Figs. 3 and 4.

Referring more particularly to the drawings, the burglar alarm system of Figs. 1 and 2, constituting one exemplary embodiment of the invention, in this instance primarily adapted for house doors, is shown in operating association with a conventional swinging door 6 mounted within a frame 7. The door 6 is provided with a conventional lock 8, the details of which per se form no part of the present invention and hence are not fully disclosed. It is sufficient to state that the lock 8 comprises a suitable frame 9 secured within the outer swinging edge of the door 6, and enclosing a normally extended spring actuated latch 10 retractable by means of a door knob 11, and a rectangular sliding bolt 12 shiftable into either projected or retracted position by means of a key (not shown).

A keeper plate 13 is inset within and rigidly secured to the inside face of a door jamb 14,

2

forming part of the door frame 7. More particularly, the plate 13 is formed with two vertically spaced rectangular openings 15 and 16 adapted respectively to receive the latch 10 and bolt 12 when the door 6 is closed. Normally, a recess 17 is formed in the jamb 14 back of the plate 13 to provide clearance for the latch 10 and bolt 12.

The present burglar alarm system comprises 10 a self-contained control switch unit 18 which is associated with the plate 13 for actuation by the latch 10 and bolt 12, and which is operatively connected in a suitable electric alarm circuit. The preferred arrangement is such that the alarm 15 circuit is disabled when the bolt 12 is retracted to unlock the door, and is conditioned for operation when the bolt is projected through the opening 16 so as to emit an alarm signal in the event and whenever the latch 10 is retracted by 20 rotation of the hand knob 11. More particularly, the switch unit 18 comprises a vertical elongated plate or other suitable support 19 of electrical insulating material connected at opposite ends by inwardly extending brackets 20 to the inner face of the plate 13.

Mounted in the upper portion of the support 19, in alignment with the uppermost opening 15, for actuation by the latch 10, is a normally closed switch 21 having fixed spaced button contacts 22, and a movable disc contact 23 adapted to bridge the fixed contacts. The contact 23 is fixed on an actuating stem 24 extending slidably through the support 19. A circular abutment head or flange 25 is fixed on the forward end of the stem 24, and is disposed for end engagement by latch 10. A coil compression spring 26 about the stem 24 between the support 19 and the head 25 tends to urge the contact 23 toward and into bridging engagement with the contacts 22. Thus, the switch 21 will close when the knob 11 is rotated to retract the spring latch 10 as, for example, when opening the door 6, and will be opened when the knob is released to release the latch for engagement with the head 25 if the door is in closed position.

45 A normally open switch 27 is mounted on the lower portion of the support 19 in position to be closed by the sliding bolt 12, which acts as a movable bridge contact. The switch 27 comprises two spaced parallel spring contacts 28 and 29, each preferably in the form of a bowed strap or leaf secured at one fixed end by means of a rivet 30 to the support 19, and disposed at the other free end partially across the opening 16 in the path 50 of the bolt 12. Thus, when the door 6 is in closed position, the switch 27 will be closed by the bolt 12 when the door is locked to condition the alarm circuit for operation, and will be opened when the door is unlocked to disable the alarm circuit.

55 The electric alarm circuit may be of any desired character. In the present arrangement, the

control switches 21 and 27 are connected therein in series, a line 31 leading from one of the contacts 22 to the spring contact 28. The other of the contacts 22 of the switch 21 is connected through a line 32 to an alarm signal device which may be of any suitable character, and which is shown as an electrically operated bell 33. Thence the circuit continues through a line 34 to one terminal of a suitable source of electric current, such as a storage battery or service main indicated at 10 35. The other terminal of the source 35 is connected through a line 36 to the spring contact 29 of the switch 27 to complete the circuit. Preferably, the switch unit is enclosed in a housing 38 fitted within the recess 17. It will be obvious that the bell 33 will be operated to give an alarm signal when both switches 21 and 27 are closed, and that the switches will both be closed when the door is locked to project the bolt 12, and the handle 11 is then turned to retract the latch 10 20 in any attempt to open the locked door.

If desired, a hand switch S may be connected in the circuit in parallel with the switch 27. When the switch S is closed, the alarm circuit will be conditioned for operation through actuation of the knob 11 whether or not the door 6 is locked. Thus, rotating the knob to open the door would produce an alarm signal.

The modified form of invention adapted primarily for use in automobile doors and illustrated in Figs. 3, 4 and 5, is generally similar to that of Figs. 1 and 2, and corresponding parts thereof are, therefore, identified by the same reference numerals distinguished by the letter "a." In this instance, the leaf spring contacts 28a and 29a are disposed on the opposite side of the support 19a, and instead of being bridged directly by the bolt 12a are adapted to be closed by a movable contact 37 operable by the bolt 12a. The contact 37 is fixed on a stem 39 extending slidably through the support 19a, and having a collar or flange 40 on the forward end engageable by the bolt 12a. A coil compression spring 41 about the bolt between the support 19a and the collar 40 tends to urge the contact 37 out of engagement with the spring contacts 28a and 29a and into engagement across two other spaced fixed contacts 42 on the rear of the support. One of the contacts 42 is connected through a line 43 to the line 34a. The other of the contacts 42 is connected through a line 44, ignition switch 45 and a line 46 to the ignition plug system 47 of an automotive engine, in turn connected through a line 48 to the line 36a to complete the ignition circuit.

In operation, when the car door is unlocked, the bolt 12a will be retracted to open the alarm circuit at the contacts 28a and 29a and to close the ignition circuit at the contacts 42. As a result, the circuit through the alarm signal device 33a is interrupted to disable the burglar alarm system. At the same time, the ignition circuit is conditioned for operation so that the engine can be started when the ignition switch 45 is closed. When the automobile door is locked, the bolt 12a will be projected into the switch unit 18a to open the contacts 42, thereby disabling the ignition circuit, and to close the contacts 28a and 29a by the contact 37, thereby conditioning the burglar alarm circuit. Under this condition, the spring latch 18a when projected through the opening 15a in the plate 13a will interrupt the alarm circuit. However, if the door handle should be actuated in an attempt to open the locked door, the switch 21a will close to effect energization of the signal device 33a.

It will be evident that I have provided a new and improved burglar alarm system adapted for various types of doors, and capable of simple operative assembly with conventional door locks of the double bolt type. As long as the door is unlocked, the alarm system is disabled. However, whenever the door is locked, tampering with the knob or handle will cause the signal device to give an alarm.

I claim as my invention:

1. A combination burglar alarm and ignition system for automobile door locks of the type having a handle actuated spring latch and a key operated sliding bolt, said system comprising, in combination with a plate for mounting in the door frame and formed to receive said latch and said bolt, an alarm circuit having an alarm device therein, an ignition circuit, said circuits including a common source of current, an insulating support adapted to be mounted in spaced relation back of said plate, a normally closed switch having two terminals connected in series in said alarm circuit, said switch being mounted on said support for engagement by said latch to open the switch when projected through said plate, a second switch mounted on said support in position for operation by said bolt and having a first pair of terminals in series in said alarm circuit, a second pair of terminals in series in said ignition circuit, and having an actuator including two mechanically coupled but electrically insulated contact members for alternatively connecting the terminals of said pairs, said actuator being normally biased so that one of said contact members connects said second pair of terminals and being operable upon engagement thereof by said bolt upon its projection through said plate into locking position to open the connection between said second pair of terminals and connect said first pair of terminals by engagement thereof by the other of said contact members, whereby retraction of said latch will cause said device to emit an alarm signal.

2. A combination burglar alarm and ignition system for automobile door locks having a spring latch and a locking bolt comprising, in combination, an alarm circuit including an alarm signal device, an engine ignition circuit, and a control switch unit comprising two switches in said alarm circuit operable respectively by said latch and bolt to disable said alarm circuit when said door is unlocked, to condition said alarm circuit for operation when said door is locked and said latch is in normal position, and to close said alarm circuit when said door is locked and said latch is moved out of normal position, and a third switch in said ignition circuit mechanically coupled with one of said two switches and operable to close when said bolt is withdrawn to unlock the door and to open when said one switch is closed upon locking of the door.
